ELECTRIC SWITCH

Carl A. Schaefer, Milwaukee, Wis., assignor to
 Square D Company, Detroit, Mich., a corpora-
 tion of Michigan

Application April 29, 1949, Serial No. 90,441

11 Claims. (Cl. 200—47)

This invention relates, in general, to adjustable electric switches and more specifically to limit switches for changing the character of an electric circuit supplying a machine when a moving part of that machine has moved beyond a desired limit.

Where devices of this type are employed, it is the practice to set the limit switch in position within the operative limits of the moving portion of the machine. The initial positioning frequently, however, determines only roughly the degree of movement to be permitted to this moving portion and subsequent, finer adjustment is in that case necessary. This finer adjustment in older devices required changing the position of a switch actuating mechanism associated with the moving part, this change occasionally being relatively minute and effected only with difficulty. It is, therefore, one object of this invention to provide a limit switch which is itself readily adjustable to vary the position at which a moving element of an associated machine will cause the character of the electric circuit supplying that machine to be changed.

Another object of this invention is the provision of a limit switch having an operator whose normal position may be varied by rotating a shaft having eccentrically mounted means, the shaft being an integral part of the switch.

Another object of this invention is the provision of an adjustable limit switch provided with an operating member which may be selectively moved inwardly or outwardly to vary the position at which a moving part of an associated machine operates the switch.

Other objects and features of the invention will be readily apparent to those skilled in the art from the specification and appended drawing illustrating certain preferred embodiments in which:

Figure 1 is a rear elevational view of the device of the present invention.

Figure 2 is a vertical sectional view along the line II—II of Figure 1.

Figure 3 is a detailed sectional view along the line III—III of Figure 1.

The device of the present invention comprises an electric switch 1 having suitable switching contacts (not shown) mounted to a metal base 2 of a generally rectangular boxlike shape. Provided as operating means for the switch is a spring lever 3 having one end 4 extending through a suitable hole in the lower end of an actuating lever 5, the end 4 consisting of a straight wire section of sufficient length to permit

raising and lowering of the lever 5, as subsequently described, without disengagement of the end 4 therefrom. The lower end of the lever 5 is biased to the left as illustrated in Figure 1 by a spring 6 mounted upon the studs 7 and 8 between the lever 5 and the inner wall of the base 2. The base is provided with a flanged section through which a plurality of mounting holes 9 extend, and may also have a gasket 11 upon the inner surface to insure a sealing connection with a mounting surface or a back cover.

Disposed for reciprocal movement within a hole 12 in the upper portion of the base 2 is a plunger 13, the upper portion of the hole 12 being provided with a bushing 14 seating upon a packing washer 15. The bushing 14 is secured in position by cooperation between a threaded section over part of its periphery and a similar section within the hole 12 as shown at 16. The lower end of the plunger 13 extends through the upper portion of the base 2 and is provided with a slot into which a retaining ring 17 is fitted which serves to maintain in position a thin washer 18 against which a spring 19, compressed between the washer 18 and the inner surface of the base 2, acts. The spring 19 insures that the lowermost end of the plunger 13 firmly seats upon a flange ear 21 of the upper horizontal section of the actuating lever 5.

There is disposed through a suitable hole through the front wall of the base 2 a rotatable shaft 22, having a head at its inner end which seats upon a bossed section 23 of the inner surface of the base. The inner end of shaft 22 is provided with a threaded hole whose axis is eccentric to the rotation axis of shaft 22 and which receives a cooperating screw 24 having a collar 25, about which uppermost end 26 of the actuating lever 5 is rotatably mounted.

The section of the rotatable shaft 22 which is exterior to the front face of the base is threaded, and has a cutaway portion on which is keyed a controlling and indicating sector 29. The nut 31 is threaded on shaft 22 to lock the sector 29 and shaft 22 in adjusted position.

The operation of the device will now be briefly described:

When the moving part of the associated machine which it is desired to restrict within certain limits, or a cam or push rod cooperating therewith, reaches the limiting position, this part or cooperating device moves the plunger 13 inward against flange ear 21 to move actuating lever 5 in a counterclockwise direction (Figure 1) 55 against the bias of the spring 6. The lower end

of the lever 5 moves to the right from the position shown in Figure 1, moving spring operating means 3 to operate switch 1. In the device of the present invention, the switch operating mechanism is adjusted to the limit of movement of the moving part by loosening the nut 31 and rotating the controlling sector 29 to rotate shaft 22. The axis about which the shaft 22 turns has been assigned the numeral 27 in Figure 3; the axis of screw 24 and collar 25 has been assigned the numeral 28. It will readily be seen that rotation of the shaft 22 will cause the axis 28 to describe an arc about the axis 27, thus effectively raising and lowering the collar 25 and actuating lever 5. This raises and lowers the ear 21 to cause the plunger 13, which is biased to contact the projection 21 by the spring 19, to project a further or lesser distance beyond the upper face of the bushing 14 and therefore adjusts the point of operation of switch 1. In adjusted position the parts are again locked by the screw 31.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In a limit switch, electrical switching means, a movable actuator for said switching means, an operator for said actuator, rotatable means, and means eccentric to the axis of rotation of said rotatable means and movable thereby to shift the position of said actuator upon rotation of said rotatable means to change the normal position of said operator.
2. In a limit switch, electrical switching means, rotatable means, means eccentric to the axis of rotation of said rotatable means, a movable actuator for said switching means movable with said eccentric means upon rotation of said rotatable means, an operator for said actuator, and means mounting said operator in engagement with said actuator whereby movement of said actuator by rotation of said rotatable means effects movement of the operator to an adjusted normal position.
3. In a limit switch, electrical switching means, rotatable means, means eccentric to the axis of rotation of said rotatable means, a movable actuator for said switching means pivotally mounted upon said eccentric means and movable therewith upon rotation of said rotatable means, and an operator for said actuator whereby movement of said actuator by said rotatable means effects movement of the operator to an adjusted normal position.
4. In a limit switch, electrical switching means, a movable actuator for said switching means, an operator for said actuator, means pivotally mounting said actuator, and means for bodily moving the pivotal axis of said actuator in a direction having at least a component in the direction of movement of the operator whereby to effect movement of the switch operator to an adjusted normal position.

5. In a limit switch, electrical switching means, a movable actuator for said switching means, an operator for said actuator, a rotatable shaft, means pivotally mounting the actuator on said shaft for normal rotation about an axis eccentric to the axis of rotation of said shaft, and means for manually rotating said shaft to move the pivotal axis of the actuator and effect movement

of the operator to an adjusted normal position.

6. In a limit switch, electrical switching means, a movable actuator for said switching means, an operator for said actuator biased into engagement therewith, a rotatable member, a stud threaded into said member and having a collar portion upon which said actuator is pivotally mounted with the pivotal axis of the actuator eccentric to the axis of rotation of said member, means biasing said actuator against movement of said operator, and means for manually rotating said rotatable member to move the pivotal axis of the actuator to move the operator to an adjusted normal position.

7. In a limit switch, electrical switching means, a movable actuator for said switching means, an operator for said actuator biased into engagement therewith, a rotatable member, a stud threaded into said member and having a collar portion upon which said actuator is pivotally mounted with the pivotal axis of the actuator eccentric to the axis of rotation of said member, means biasing said actuator against movement of said operator, means for manually rotating said rotatable member to move the pivotal axis of the actuator to move the operator to an adjusted normal position, the bias on said actuator being stronger than the bias on said operator so as to maintain the actuator in non-operated position while biasing the operator into engagement with the actuator.

8. In a limit switch, electrical switching means having first operating means therefor, an actuator for said operating means, second operating means for said actuator, means connecting said actuator and said second operating means whereby movement of said actuator effects movement of said second operating means, rotatable means, and means eccentric to the axis of rotation of said rotatable means and movable thereby to shift the position of said actuator relative to said first operating means upon rotation of said rotatable means whereby said second operating means is moved to an adjusted normal position.

9. In a limit switch, electrical switching means having first operating means therefor, a pivoted actuator for said first operating means, second operating means rectilinearly movable for rotating said actuator about its pivot to effect operation of said switching means, means connecting said actuator and said second operating means whereby movement of said actuator effects movement of said second operating means, rotatable means, and means eccentric to the axis of rotation of said rotatable means and movable thereby, said eccentric means effecting movement of said pivoted actuator in a direction substantially parallel to the direction of movement of said second operating means upon rotation of said rotatable means whereby said second operating means is moved to an adjusted normal position.

10. In a limit switch, electrical switching means having first operating means therefor, an actuator for said first operating means having a sliding connection to said first operating means, second operating means rectilinearly movable for said actuator, means biasing said second operating means toward constant engagement with said actuator whereby movement of said actuator effects rectilinear movement of said second operating means, rotatable means, and means eccentric to the axis of rotation of said rotatable means and movable thereby, said eccentric means effecting movement of said actuator upon rota-

tion of said rotatable means in a direction substantially parallel to the direction of movement of said second operating means whereby said actuator and said second operating means is moved to an adjusted position without moving said first operating means.

11. In a limit switch for controlling the movement of a moving machine part and comprising an electric switch and an operator depressed by the machine part to effect the operation of the electric switch, bodily movable means interconnecting said operator and said switch, means for maintaining engagement between said bodily movable means and said operator at all times, and means slidably connecting said bodily movable means and said electric switch whereby said bodily movable means may be positioned without operating said electric switch, and means for effecting movement of said bodily movable

means relative to said electric switch and movement of said operator to adjusted position whereby the position at which said moving machine part effects operation of said electric switch may be varied.
